Inventor
JAMES G. CORBETT

UNITED STATES PATENT OFFICE.

JAMES G. CORBETT, OF BEAVER FALLS, PENNSYLVANIA.

FOUNTAIN-BRUSH.

1,093,114.

Specification of Letters Patent. Patented Apr. 14, 1914.

Application filed September 17, 1913. Serial No. 790,273.

To all whom it may concern:

Be it known that I, JAMES G. CORBETT, a citizen of the United States, residing at Beaver Falls, in the county of Beaver and State of Pennsylvania, have invented certain new and useful Improvements in Fountain-Brushes, of which the following is a specification, reference being had to the accompanying drawings.

- 10 This invention relates to improvements in fountain brushes, and more particularly to that class of brushes which are adapted for use in washing and wiping windows, doors, and other smooth surfaces.
- 15 An object of this invention is the provision of a device of this character, which comprises a tubular handle having a transversely extending apertured head, the head having a brush secured on one side thereof and a wiping device secured on the opposite side thereof, the apertures in said head facing the brush whereby the window may be washed and scrubbed when the handle is held in one position, and by reversing the 25 position of the handle, the window may be wiped.

A further object of this invention is the provision of a device of this character in which the brush and wiping device may be 30 readily removed.

With these and other objects in view, my invention consists in certain novel constructions, combinations, and arrangements of parts, to be hereinafter more fully described, 35 claimed and illustrated in the accompanying drawing, in which

Figure 1 is a view in side elevation of a brush constructed in accordance with an embodiment of my invention. Fig. 2 is a 40 fragmentary sectional view taken through the head portion of the brush disclosed in Fig. 1 and showing the same adjusted into a different position. Fig. 3 is a view in top plan and partly in section of the device 45 as illustrated in Fig. 1. Fig. 4 is a fragmentary view in side elevation of my device as herein disclosed with the brush proper omitted; and Fig. 5 is a view in top plan of the structure shown in Fig. 4.

50 Referring more particularly to the drawing, the numeral 1 designates a handle of wood or other suitable material, in which is arranged a tubular water pipe 2, the upper end of which projects above the handle and 55 is formed with a transversely extending hollow head 3. The lower end of the pipe 2

projects beyond the lower end of the handle and is threaded, as at 4, whereby a stop cock 5 may be secured thereto. The stop cock 5 is provided with a suitable valve 6, 60 and the lower end thereof is threaded as at 7 for the attachment of a suitable hose connection (not shown).

A brush 8 having a head 9 is adapted to be secured to the outer end of the pipe, the 65 brush head having a longitudinal groove 10 in its opposite edges, the groove 10 in the outer edge of the brush being adapted to engage the transversely extending head of the pipe, the groove in the inner edge of the 70 head being engaged by the intermediate portion 11 of a spring, the opposite ends of which are soldered or otherwise secured as at 12 to the pipe 2 above the handle. The back 9 of the brush is provided with a 75 recess 13 which is adapted to engage the upper extremity of the pipe 2 whereby endwise movement of the brush is prevented.

A transverse outstanding plate 14 is soldered or otherwise secured to the head 3, 80 the plate being formed with offset apertured ears 15 for the reception of a rod 16. A spring 17 having its opposite ends coiled is secured to the rod 16 as at 18 and is adapted to bear against a clamping plate 19 by means 85 of which a drier comprising a rubber strip 20 is clamped between the plates 14 and 19. The outer end of the pipe 3 is provided with a series of forwardly facing apertures 21 through which the water which enters the 90 pipe through the stop cock 5 is adapted to pass over the brush 8, whereby the window may be washed and scrubbed by the same operation.

In the practical use of my device, the stop 95 cock 5 is secured to a hose connection at its threaded end 7, and when it is desired to wash a window, door or the like, the valve 6 is opened so that the water may pass through the pipe 2 and thence through the 100 apertures 21 in the head 3 of the pipe, the water being adapted to spray against the window whereupon the brush may be moved over the surface of the window to thoroughly wash and scrub the same. When the window has been thoroughly washed, the valve 6 is closed so as to shut off the supply of water, and the position of the handle is reversed so that the rubber strip 20 may be 105 brought into use, to remove the water from the window. When it is desired to clean the brush 8 it may be readily removed from the 110

2
handle by moving the head thereof against the action of the spring 11 whereupon the groove 10 in the outer face of the head is moved out of engagement with the head 3 of 5 the pipe. The rubber strip 20 may also be readily removed from the plates, by relieving the pressure of the spring pressed plate 19 against the strip.

While the construction illustrated in the 10 accompanying drawing is the preferred embodiment of my invention, it will be understood that minor changes in construction may be resorted to, without departing from the spirit of my invention or sacrificing any 15 of its advantages as determined by the scope of the appended claims.

Having thus fully described my invention what I desire to claim and secure by Letters Patent is:

20 1. A device of the character described comprising a pipe adapted to be connected with a suitable source of fluid supply, said pipe being formed with a transversely extending apertured head on its opposite end, 25 a brush head having longitudinal grooves in its opposite edges, one of said grooves being adapted to engage the transversely extending head of said pipe, and means secured to

said pipe and adapted to engage in the groove in the opposite edge of said brush 30 head, the back of the brush head being provided with a recess to accommodate a portion of the pipe whereby endwise movement of the brush head is prevented.

2. A device of the character described 35 comprising a tubular pipe adapted to be connected with a suitable source of fluid supply, said pipe being formed with a transversely extending apertured head at its other end, a brush head having longitudinal grooves in 40 its opposite edges, one of said grooves being adapted to engage the transversely extending head in said pipe, a spring having its opposite ends secured to said pipe, and the intermediate portion of said spring being 45 adapted to engage the other groove in said brush head, the back of the brush head being provided with a recess to accommodate a portion of the pipe whereby endwise movement of the brush head is prevented. 50

In testimony whereof I hereunto affix my signature in the presence of two witnesses.

JAMES G. CORBETT.
